UNITED STATES PATENT OFFICE

141,260

DESIGN FOR A SAVINGS BANK

Hugh McMahon Garee, Minerva, Ohio, assignor to Dana K. Harvey, doing business as Chic Pottery Company, Wellsville, Ohio

Application October 25, 1943, Serial No. 111,489

Term of patent 7 years

(Cl. D34—11)

To all whom it may concern:

Be it known that I, Hugh McMahon Garee, a citizen of the United States, residing in the city of Minerva, county of Stark, and State of Ohio, have invented a new, original, and ornamental Design for a Savings Bank, of which the following is a specification, reference being had to the accompanying drawing, forming part thereof.

I claim:

The ornamental design for a savings bank, as shown.

HUGH McMAHON GAREE.
